ATTORNEY

UNITED STATES PATENT OFFICE.

GEORGE A. NORRIE, OF GENESEE, WISCONSIN.

FLUID-FUEL BURNER.

1,287,735.

Specification of Letters Patent. Patented Dec. 17, 1918.

Application filed March 9, 1918. Serial No. 221,487.

To all whom it may concern:

Be it known that I, GEORGE A. NORRIE, a citizen of the United States, and resident of Genesee, in the county of Waukesha and 5 State of Wisconsin, have invented certain new and useful Improvements in Fluid-Fuel Burners; and I do hereby declare that the following is a full, clear, and exact description thereof.

10 My invention relates to improvements in fluid fuel burners, particularly that class which is adapted to be disposed in the fire box of a cook stove or similar heater.

Inasmuch as cook ranges differ greatly in 15 size with a consequent change in the length of their fire boxes, it will obviously be an advantage to change the position of the burner heads to conform to the length of the fire box. Therefore it is the principal 20 object of the present invention to provide a fluid fuel burner which is adjustable for use in stoves or ranges of various sizes.

It is also an object to provide an improved simply constructed burner head 25 which has means for trapping any scale or foreign matter before the fuel enters the discharge portion thereof.

A further object is to provide means for increasing the efficiency of the initial generation of gaseous or vaporous fuel.

30 A still further object is to provide an improved flame spreading means which can be readily adjusted at will.

With these and other objects and advantages in view, the invention resides in the 35 novel features of construction, combination and arrangement of parts which will be hereinafter more particularly described and claimed and shown in the drawing wherein:

40 Figure 1 is a plan view partly in section of a fluid fuel burner constructed in accordance with my invention.

Fig. 2 is a longitudinal sectional view taken substantially on the plane of the line 45 2—2 of Fig. 1.

Fig. 3 is a transverse sectional view on the plane of the line 3—3 of Fig. 1, and

Fig. 4 is a detail plan view of the base plate.

50 Inasmuch as my invention is adapted for use in stoves, its specific application has not been particularly disclosed. It will be seen from the following description, however, that it may be used with any stove

without change, it being normally mounted 55 on the usual grate when the stove has heretofore been used for burning coal or wood.

Referring more particularly to the present embodiment of the invention, it will be noted that 1 indicates a flat base plate having depending peripheral flanges or walls 2 which engage the grate bars, and a pair of longitudinally arranged oval air supply openings 3. These openings are positioned to one side of the longitudinal center of the 60 base, while to the other side of such center and at the opposite ends of the plate is formed a pair of substantially semi-circular flanges 4. Each of the flanges has an open end slot 5, said slots being extended longitudinally of the base.

Associated with each of the air supply openings 3 is a frusto-conical air and flame directing member 6, the lower end of each of which being provided with a laterally extending flange 7 which has a sliding contact with the surface of said base. These members 6 are always positioned over the openings 3 so that all air entering the lower portion of the stove or the like must pass 75 through the same before reaching the burner heads to be hereinafter described. For aiding in the direction of such air to the openings 3, the space between the edge of the base and the walls of the fire box is closed 80 with suitable material.

A burner head 8 is adapted to be employed in connection with each air supply opening and its directing member. Since 90 each of these heads and the parts of the invention which supply fuel thereto is substantially alike, the description of one will suffice for both. The burner head 8 comprises an attaching arm 9, one end of which is open and integrally screw-threaded, while 95 the other end is bent laterally for engagement with a supply and generating pipe 10 positioned above the base 1 and approximately in the plane of the top of the air directing members 6. The arm 9, therefore, is 100 inclined downwardly and adjacent its lower end has a gas discharge arm 11 formed integrally therewith, said discharge arm being extended at right angles to the other arm and positioned horizontally. The discharge 105 arm is disposed through aligned openings in the wall of one of the air directing members 6 and has one or more jet openings therein.

The lower open end of the attaching arm 9 of the burner head is adapted to be normally closed by a screw plug 12, which plug permits the head to be readily cleaned and also provides for the insertion of a cylindrical filtering screen 13 of reticulated material. As shown most clearly in Fig. 1, this screen covers the passage-way between the arms 9 and 11 of the burner head, and inasmuch as such passage-way is spaced above the lower end of the attaching arm, any sediment which is separated from the fuel by the screen will fall upon the plug 12 and be thereby trapped.

15 The end of the pipe 10 remote from its connection with the burner head is threaded in an elbow 14 which in turn is mounted on the upper end of a hollow standard 15. Each of the standards 15 is adjustably disposed in one of the slots 5 so that the burner heads may be moved toward or away from each other to accommodate the burner for use in various sizes of stoves or the like. Each standard is clamped to its flange 4 by 20 clamping nuts 16 threaded thereon as most clearly shown in Fig. 2. The lower end of each standard is adapted to be connected by a union or the like 17 to the end of a fuel supply tube 18, the control of which may 25 be located outside of the stove or in any other convenient location.

The present invention is designed primarily for use in connection with liquid fuel; therefore an initial generating means 30 in the form of a pair of generator pans 19 is provided. Each of these pans has a circular portion provided with a central opening to receive the standard which is used therewith, and a laterally extending portion 35 to underlie the adjacent end of the supply pipe 10. The generator pans will thus always maintain the same relative position with respect to the standards and will be moved therewith. As is usual in devices of 40 this character, alcohol or other liquid fuel is disposed in the pans 19 for pre-heating the liquid fuel within the standards 15.

Such fuel is obviously more quickly heated and therefore more readily vaporized 45 when of small volume; therefore I dispose within each of the standards a rod 20, the diameter of said rods being slightly less than the inner diameter of the standards. The lower ends of the rods are beveled off as at 50 21 and seat on the ends of the supply tubes 18. A thin film of oil or other liquid fuel is thus disposed around each of the rods.

The burner heads are rendered more efficient and their operation more easily controlled by a pair of flame spreaders 22, one of which is positioned over each air and flame directing member 6. These spreaders are elongated so that they may be used when the burner heads are adjusted to any one of 60 their several positions, and each is connected

with a sleeve 23 that is journaled on a rod 24 between a pair of uprights 25 which rise from the base plate.

By thus pivoting the flame spreaders they may be readily adjusted toward or away 70 from the burner heads thus regulating the amount of heat directed upon the supply and generating pipe 10. They may also be used for directing the flame toward the oven of the stove or range, or if the jet openings 75 of the burner heads are to be cleaned, they may be readily swung upwardly and out of normal position. Such adjustment is procured through a crank 26 that projects from the sleeve 23 and a rod 27 pivoted thereto. Said rod extends through an opening in the front wall W of the stove and has its end threaded to receive a winged nut 28, the adjustment of which varies the position of the spreaders 22.

I claim:

1. A device of the class described adapted to be disposed in a stove or the like and comprising a supporting base having an elongated air supply opening, a burner disposed 90 over said opening, said burner being movable with respect to the opening, and means for securing the burner in adjusted positions with respect to the opening.

2. A device of the class described adapted 95 to be disposed in a stove or the like and comprising a supporting base having an elongated air supply opening, an air directing member slidable over said opening, a burner connected with said member and movable 100 therewith, said burner being adapted to be adjusted with respect to the opening, and means for securing the burner in adjusted positions.

3. A device of the class described adapted 105 to be disposed in a stove or the like and comprising a supporting base having a pair of spaced elongated air supply openings, an air directing member slidable over each of said openings, a pair of burners, one being 110 adapted to be secured to each of said air directing members, the latter being movable therewith, said burners being adapted to be moved toward or away from each other, and means for securing said burners and the air 115 directing members in adjusted positions with respect to each other and to said openings.

4. In a device of the class described, a horizontally positioned base plate having 120 an open end slot, a vertically disposed burner standard movable lengthwise of said slot, a burner head connected with said standard, and spaced clamping means on said standard to grip said plate therebetween to hold the burner in adjusted positions.

5. A burner head comprising a vertically inclined attaching arm open at its opposite ends, a closure plug for the lower end of the 130

- arm, a fuel supply pipe connected with the upper end of said attaching arm, a gas discharge arm extending at right angles from the attaching arm intermediate the ends thereof and disposed horizontally, and a screen in the attaching arm and disposed over the communicating opening between the two arms, said screen resting on said plug.
- 10 6. A device of the class described comprising a hollow, substantially vertically disposed burner standard, a burner head connected with the upper end of said stand-

ard, a fuel supply tube of less diameter than the standard connected with the lower end thereof, and a rod disposed in said standard, said rod being of approximately the diameter of said supply tube and having its lower end resting on the inner end thereof, said end of the rod being beveled off to prevent the closing of said tube.

In testimony that I claim the foregoing I have hereunto set my hand at Milwaukee, in the county of Milwaukee and State of Wisconsin.

GEORGE A. NORRIE.
